UNITED STATES PATENT OFFICE.

RICHARD H. THOMAS, OF KID'S GROVE, NEAR STOKE-ON-TRENT, ENGLAND.

IMPROVEMENT IN RUDDERS.

Specification forming part of Letters Patent No. 132,991, dated November 12, 1872.

To all whom it may concern:

Be it known that I, RICHARD HANDLY THOMAS, of Kid's Grove, near Stoke-on-Trent, England, have invented a new and useful Improvement in Rudders for Vessels, of which the following is a specification:

My invention consists of a rudder of two blades, arranged side by side, one on each side of the axis, and distant from each other so as to allow a solid flow of water between them, connected at top by a horizontal bar or disk to the axis or shaft; also connected in like manner at the bottom to a pivot stepped in the projecting end of the keel, and also divided at or near the middle vertically, and similarly connected by disks or bars to a journal fitted in a block in which the projecting end of the propeller-shaft is also journaled, so as to strengthen the rudder and support the propeller-shaft, all as hereinafter described.

Figure 1 is a side elevation of the rudder-propeller and part of a ship's hull, with the bearings of the rudder-shaft sectioned; Fig. 2 is a rear elevation of the rudder; Fig. 3 is a top view; and Fig. 4 is a horizontal section of Fig. 3 on the line $x x$ of Fig. 2.

Similar letters of reference indicate corresponding parts.

A and A' represent the two propeller-blades, placed side by side on opposite sides of the axis, and connected at the top to the shaft B by a horizontal disk, C, also connected at the lower ends to the pivot D by a disk, E. Op-

posite the propeller-shaft F these blades are divided, and they are connected by the disks G to a journal, H, between said disks, which is fitted in bearing-block I, in which the propeller-shaft has also a bearing, K, by which the blades are greatly strengthened and the propeller-shaft is considerably supported. The disks are provided with numerous large holes, L, to relieve them from lifting the water or being resisted by it as the stern of the vessel rises and falls.

Two blades in this arrangement, being eccentric to the longitudinal vertical axis, have more than double the power of one blade of the same size arranged in the axis, and being centered with the axis as to its transverse plane they are balanced as to each other, also as to the axis, so they can be operated as easily as a single-balanced blade can be.

Having thus described my invention, I claim as new and desire to secure by Letters Patent—

A rudder of two blades, A A', arranged side by side on opposite sides of the axis, as described, divided opposite the propeller-shaft, and provided with a journal thereat, with a bearing-block fitted on it, and receiving the journal on the propeller-shaft, substantially as specified.

RICHARD H. THOMAS.
